UNITED STATES PATENT OFFICE.

WILLIAM T. SMITH, OF PHILADELPHIA, PENNSYLVANIA.

DESIGN FOR A RUG.

SPECIFICATION forming part of Design No. 19,606, dated January 21, 1890.

Application filed December 23, 1889. Serial No. 334,751. Term of patent 3½ years.

To all whom it may concern:

Be it known that I, WILLIAM T. SMITH, a citizen of the United States, residing at Philadelphia, in the county of Philadelphia and 5 State of Pennsylvania, have invented and produced a new and original Design to be Woven in Chenille Rugs and Curtains, of which the following is a specification, reference being had to the accompanying photographic print, forming a part thereof, which conveys to any one skilled in the art of chenille-weaving a clear understanding of the same, and is sufficient to enable such person to use my invention.

What I claim as my invention, and desire 15 to secure by Letters Patent, is—

The design for a chenille rug or curtain, consisting in the ornamentations shown in the photographic print accompanying this specification.

W. T. SMITH.
